O. KVARE

CLOTHES CARRIER

Filed Oct. 26, 1925

Patented Apr. 17, 1928.

UNITED STATES PATENT OFFICE.

OLEA KVARE, OF MCINTOSH, MINNESOTA.

CLOTHES CARRIER.

Application filed October 26, 1925. Serial No. 64,847.

This invention relates to a clothes carrying device, such as a trunk or grip, and particularly to such a device arranged to carry garments or dresses in such a manner that they will not be creased or wrinkled. When taking short trips, persons commonly pack some extra garments in a grip. If such garments, particularly ladies' dresses, are folded and placed in the grip they become quite mussed and creased and usually necessitate pressing before being worn. This creasing and mussing of dresses occurs even if they are in a folded condition in a grip for a short time and is a great inconvenience.

It is an object of this invention, therefore, to provide a clothes carrying device having means on which the garments, such as dresses, are disposed so that the same may be carried without creasing or mussing.

It is a further object of the invention to provide a clothes carrying device having a casing, a carrier therein having a smooth exterior surface, such as a cylindrical or partly cylindrical surface about which the garment is wrapped, means being provided for holding the garment on the carrier and for properly supporting the carrier in the casing.

It is still a further object of the invention to provide such a clothes carrying device, as set forth in the above paragraph in which a second carrier may be used surrounding the first carrier and the garments thereon, said second carrier also having a smooth exterior surface about which a garment may be wrapped, means being provided for holding the garment on said second carrier and for properly supporting said carrier in spaced relation to said first carrier.

It is more specifically an object of the invention to provide a clothes carrier comprising a plurality of carriers with smooth exterior surfaces adapted to have garments, respectively, wrapped thereon, one or more of which carriers may be held in various positions with different sizes of surfaces, together with means for holding the garments on the carriers and for properly supporting the carriers in the device and holding the same in proper position.

These and other objects and advantages of the invention will be fully set forth in the following description made in connection with the accompanying drawings in which

like reference characters refer to the same parts throughout the different views, and in which,

Fig. 1 is a perspective view of the device embodying the invention, portions thereof being broken away to show the interior;

Fig. 2 is a transverse vertical section taken substantially on the line 2-2 of Fig. 1, as indicated by the arrow, showing the lid in open position;

Fig. 3 is a vertical section taken substantially on the line 3-3 of Fig. 1, the interior portion being shown partly in side elevation and partly in vertical section;

Fig. 4 is a vertical section taken substantially on the line 4-4 of Fig. 3, as indicated by the arrows, one of the carriers being shown in open position; and

Fig. 5 is a section also taken substantially on the line 4-4 of Fig. 3, showing garments on both carriers.

Referring to the drawings, a clothes carrying device is shown comprising an outer casing. While this casing may be a casing of a trunk or other clothes carrying receptacle, in the embodiment of the invention illustrated the same is shown as in the form of a hand grip, said casing being designated 6 and being partly cylindrical in form with flat ends 6^a and a flat bottom 6^b. The casing is provided with a lid 7 hinged along one longitudinal edge, which lid is also flat and substantially of the width of the bottom 6^b, the same having a flap 7^a adapted to extend down over the side of the casing 6. The lid 7 has secured thereto a bail strap handle 8 of ordinary form, and while any desired means may be provided for holding the lid in closed position, in the embodiment of the invention illustrated, said handle is shown as having keepers 8^a at its ends through which may extend the straps 9 having buckles 10 thereon adapted to hold the lid 7 in closed position. A carrier 11 is provided in casing 6 having a smooth exterior surface and, while this carrier may be of various forms, in the embodiment of the invention it is shown as substantially cylindrical. Said carrier is closed at one end and provided at its other end with a detachable flanged lid 12 which may be screwed on, whereby any desired and suitable article, such as an umbrella may be carried within said carrier. The carrier 11 is adapted to

have one or more garments, such as dresses, wrapped about its periphery and said carrier is provided adjacent its ends with means, such as clasp pins 13 for holding said garments in proper position thereon. In the embodiment of the invention illustrated the pins 13 are shown as in the form of ordinary safety pins and are carried by straps 14 adjustably held in buckles 15 carried by 10 short straps 16 secured to the carrier 11 adjacent the ends thereof. The carrier 11 is removably supported in semi-cylindrical flanges 17 supported at each end of the casing 6 and when said carrier is placed in 15 the flanges 17 and the lid closed, the same is held firmly in stationary position by being engaged by the resilient prongs 18 secured to the inside of lid 7 and having their ends curved outwardly so as to snugly 20 embrace the carrier 11.

A second carrier 19 is provided also having a smooth exterior surface. While this second carrier may also be of various forms, in the embodiment of the invention illustrated, the same is shown as in the form of a cylinder made of somewhat flexible material adapted to maintain its cylindrical form, said cylinder being open at one side and provided at each end with a plurality of detachable fasteners 20, any one of which is adapted to be engaged by a co-operating fastener 21 carried on the other free edge of said carrier. While any suitable fastener means may be used, in the embodiment of 30 the invention illustrated, the fasteners 20 and 21 are shown as the ordinary ball and socket snap fasteners. The carrier 19 is also adapted to have one or more garments wrapped about its exterior and said carrier is also provided with strips 22 carrying buckles 23 adapted to be adjustably secured thereto that can grip the strap 14 shown in Fig. 3. The end 6^a of the casing is also provided with semicylindrical flanges 24 extending outwardly beyond the flanges 17, which flanges 24 are adapted to receive the ends of the carrier 19 so that the same may be readily placed therein or removed. When the carrier 19 is supported on flanges 24 and lid 7 closed the carrier is adapted to be engaged by the ends of a bow spring 25 secured to the lid 7 so that carrier 19 is held firmly in the flanges 24. The garments wrapped about the carriers 11 and 19 may be additionally held in position by one or more tapes 26 tied somewhat loosely thereabout.

In operation, when it is desired to carry a garment, such as a dress or other garment 60 the lid 7 of the casing 6 will be opened. The carriers 11 and 19 can then be lifted from their supports 17 and 24. The articles desired to be carried in the carrier 11 can then be placed therein and the lid 12 placed thereon. One or more garments B,

such as dresses, can now be loosely wrapped about the carrier 11. By wrapping the dresses loosely and carefully about the exterior surface of the carrier the dress will not be creased or mussed. The dress or other garment can be held from longitudinal movement on the carrier and held in proper position thereon by engaging suitable portions thereof by the pins 13 and, if desired, one or more tapes 26 can be wrapped thereabout. Dresses are thus loosely and efficiently supported. If desired, sheets of tissue paper may be disposed between the layers of the dresses or between the various dresses on the carrier. After the garments 70 are thus placed on carrier 11 the carrier 19 will be adjusted to proper size by engaging the fasteners 20 and 21 so as to pass loosely over the garments B on carrier 11. Additional garments C can then be disposed 75 about the carrier 19 in the same manner as those disposed on carrier 11. These garments will also be held by the pins 13 carried on the strips in buckles 23 and the garments may be additionally held by tapes 26, if desired. With the garments thus disposed on carriers, the carriers may be inserted through the top of casing 6 and the ends of the carriers seated in the flanges 17 and 24. Even if the diameter of the garments on carrier 19 is slightly greater than the width of the opening at the top of casing 6 they can be conveniently inserted in the casing by a slight pressure at the side which will be immediately relieved when the carrier is in position in the casing. The carriers with the garments thereon now being disposed in the casing 6, the lid 7 can be closed and the carriers will be firmly held in position in the casing and prevented for moving by engagement thereon of the resilient members 18 and 25. These members are so proportioned that both carriers will be snugly engaged. The grip can now be secured in closed position and carried in an automobile, under the seat 90 of a train or any other desired convenient place. It will be noted that garments will not be folded or creased but are carried in continuous unfolded length so that there will be no appreciable massing or creasing 95 thereof.

From the above description it is seen that applicant has provided a very simple and efficient clothes carrying device and one in which garments may be compactly carried 100 and yet prevented from objectionable massing, wrinkling or creasing. The utility of the device had been demonstrated in actual practice.

It will, of course, be understood, that various changes may be made in the form, details, arrangement and proportions of the parts without departing from the scope of applicant's invention, which, generally stated, consists in a device capable of carry- 110 120 130

ing out the objects above set forth, in the novel parts and combinations of parts disclosed and defined in the appended claims.

What is claimed is:

5. 1. A clothes-carrying device having in combination, a casing, a readily removable carrier therein having a substantially continuous smooth exterior peripheral surface adapted to have a garment wrapped thereon about and supported thereon, means for holding said garment on the exterior of said carrier, and means for supporting said carrier in said casing in a stationary position so that said carrier and garment thereon are 15 spaced from the walls of said casing.
2. A clothes carrying device comprising a casing, a removable carrier therein having a substantially smooth exterior surface adapted to support a garment on said surface, said carrier being hollow, a removable lid for said carrier, means at the ends of said carrier for holding a garment on the exterior thereof, means for supporting the end portions of said carrier and lid in said casing, and means for holding the same in a stationary position therein.
3. A clothes-carrying device having in combination, a casing, a removable substantially cylindrical carrier therein, means for holding a garment wrapped about the exterior of said carrier, a second readily removable and substantially cylindrical carrier surrounding said first mentioned carrier, and means for supporting and holding said carriers in stationary position in said casing in spaced relation and in spaced relation to said casing.
4. A clothes-carrying device having in combination, a casing having semi-cylindrical sides a plurality of removable nested carriers having substantially smooth exterior surfaces in said casing adapted to have garments wrapped thereabout, means for holding said garments on said carriers, means for supporting said carriers in spaced relation to each other and to said casing and a lid hinged along a longitudinal element of one of said sides.
5. A hand grip having in combination, an elongated casing having substantially semi-cylindrical sides, a lid hinged thereon along the longitudinal element of said casing, a carrier in said casing having a substantially smooth exterior peripheral surface adapted to have a garment wrapped about said surface, means for holding said garment on said carrier, and means at the ends of said casing for removably supporting said carrier spaced from said casing.
6. The structure set forth in claim 5, and means on said lid for holding said carrier in stationary position.
7. A hand grip having in combination, an elongated casing, a lid hinged thereon about a longitudinal element thereof, a carrier in said casing having a substantially smooth cylindrical exterior surface adapted to have a garment wrapped about said surface, means for holding said garment on said carrier, a second carrier also having a substantially smooth cylindrical exterior surface and surrounding said first mentioned carrier and adapted to have a garment wrapped about its exterior surface, means for holding a garment on said second carrier, and means at the ends of said casing for supporting said carriers in spaced relation and spaced from said casing so that said carriers are readily removable.
8. A hand grip having in combination, a casing, a hinged lid thereon, a carrier in said casing having a substantially smooth exterior surface adapted to have a garment wrapped about said surface, means for holding said garment on said carrier, a second carrier also having a substantially smooth exterior surface and surrounding said first mentioned carrier and adapted to have a garment wrapped about its exterior surface, semi-cylindrical flanges at the ends of said casing respectively in which said carriers are supported, and means on said lid for engaging said carriers and holding the same in stationary position.
9. A clothes carrying device comprising an elongated casing, a readily removable carrier therein having a continuous substantially smooth peripheral surface, means for holding a garment on said surface and wrapped about the same and means in said casing for supporting the ends of said carrier so that said surface and garment are spaced from the walls of said casing.

In testimony whereof I affix my signature.
